UNITED STATES PATENT OFFICE.

WILLIAM W. MATHES, OF STOCKTON, CALIFORNIA.

METHOD OF OBTAINING CONTACT IN PROCESSED-PAPER PRINTING.

Application filed June 1, 1923. Serial No. 642,752.

This invention relates to what is commonly known as the blue-printing industry, in which negatives and blue or other prints are obtained from drawings, etc., on tracing cloth or paper, or from negatives first obtained from the same, by exposure to the light.

It is essential to obtain good results from any tracing or negative that the contact between the latter and the paper on which the print is being made shall be good, as otherwise a blurred effect will be had. This is frequently hard to obtain however owing to creases, bulges and the like in one or the other of the contacted sheets. To overcome this, vacuum printing frames are commonly used, which necessitates a considerable outlay for air pumps and the accessories which go with the same. This system, while good, is expensive to operate, and the high negative pressures sometimes used are apt to cause the glass of the printing frame to be broken.

The principal object of my invention therefore is to eliminate the above named expense and defects of operation by providing method for obtaining excellent contact without the use of mechanism of any character, with a small initial cost, and without any expense for operation.

The manner in which I attain my ends will be made fully evident by a further perusal of this specification, reference being had to the accompanying drawing, the figure on which is a perspective view of a blue printing frame of ordinary character, showing my contact-obtaining means therein.

Referring now more particularly to the characters of reference on the drawing, the numeral 1 denotes the frame, having the usual smooth glass 2 against the inner face of which the negative or tracing 3 is placed, on which in turn the sheet of processed paper 4 to be printed, is laid.

To obtain the desired and necessary contact between the sheets 3 and 4, I employ a fairly heavy sheet or pad 5 of pure rubber,

having a smoother surface, absolutely true and level, and the size of the frame.

In placing this pad over the sheets 3 and 4, it is first rolled up as shown, and placed at one end of the frame, in such a manner that the unrolling of the pad will cause the same to extend toward the other end of the frame.

The pad, being heavy and very flexible will, as it unrolls, lie absolutely flat on the sheets thereunder, forcing all air from between the sheets, and by reason of its weight and rolling movement, flattening out all creases and the like therein as the pad advances. Apart from its weight however, the exclusion of the air from between the sheets, and from between the uppermost sheet and the pad, will cause a certain suctional influence to be set up between the pad and the members thereunder, so that the normal pressure of air on the outer surface of the pad will be added to its weight to cause the pad to be firmly held against the sheets, and the latter against themselves.

Though it may be possible to effect this exclusion of the air, which is one of the main features of my method, by other means than by unrolling the pad, this is such a simple and quickly performed operation, that I feel it is the only practical method to employ.

It is also essential of course that the pad shall be air proof, and quite flexible and heavy, so that when the pad is rolled up it will have a tendency to unroll under its own flexibility and weight and thus as it unrolls and lays flat against the sheet it will automatically expel the air from between the pad and sheet.

Here again, while there may be other materials than rubber suitable for the purpose, I feel that rubber, of the proper quality and weight, is the best material obtainable.

It will therefore be evident that I have provided a method and device for the purpose which will be very efficient in operation, whether for small or large frames.

Such a pad is also adaptable for use in the automatic feed blue-printing machines, in place of the usual canvas belting, with excellent results.

Having thus described my invention what I claim as new and useful and desire to secure by Letters Patent is:

The method of obtaining contact between superimposed sheets laid on a smooth surface consisting in placing on said sheets a

pad of heavy flexible and air proof material rolled on itself, and allowing the pad to unroll over the sheets under the influence of its own weight and resiliency whereby with such unrolling of the pad the air between the pad and sheets will be positively excluded.

In testimony whereof I affix my signature.

WILLIAM W. MATHES.
